BOX FORMING MECHANISM

Original application filed July 1, 1925, Serial No. 40,769. Divided and this application filed December 31, 1926. Serial No. 158,183.

Our invention relates to the art of constructing or wrapping boxes, either stayed or non-stayed, packages, box structures, or the like, hereinafter generically termed "box structures".

In accordance with our invention, individual box structures and wrapper sheets or labels having one surface either partially or wholly coated with adhesive are delivered in succession into the path of the form block structure of a wrapping machine or the like, and for transporting the box structures toward said path there is utilized a member or structure reciprocating in timed relation with the wrapping machine.

Further in accordance with our invention, there is utilized conveying mechanism for transporting individual box structures in succession into the path of the wrapping machine form block structure, to which conveying mechanism the aforesaid reciprocating member, preferably moving in a path parallel with that of the form block structure, delivers box structures in succession, and more particularly, a box structure of the character last named may be one or more separate components of cardboard, box board, or the like destined to be held in box-forming position by a wrapper, sheet or label.

Further in accordance with our invention, a blank destined to form a non-stayed box is passed through bending and forming mechanism, and in the form of a non-stayed box is moved to suitable position with respect to the wrapper-applying structure of a wrapping machine; and more particularly, the aforesaid bending and forming mechanism comprises one or more plungers reciprocating in timed relation with the wrapping machine.

Our invention resides in the system and apparatus of the character hereinafter described and claimed.

This application is a division of our pending application Ser. No. 40,769, filed July 1, 1925.

For an understanding of one of the forms our apparatus may take, reference is to be had to the accompanying drawings in which:

Fig. 1 is a side elevational view, partly in

vertical section of apparatus constructed in accordance with our invention.

Fig. 2 is a transverse vertical sectional view taken on the line 2—2 of Fig. 1.

Fig. 3 is a plan view of the structure shown in Fig. 1.

Fig. 4 is transverse vertical sectional view taken on the line 4—4 of Fig. 3.

Referring to the drawings, there is illustrated a wrapping machine W generally of the character illustrated in U. S. Patent No. 691,329. However, in accordance with the preferred form of our invention, wrapping machine W is of the character illustrated in U. S. Patent No. 1,540,900 or in our U. S. Patent No. 1,541,036.

In the example illustrated, the wrapping machine W comprises a reciprocatory rod 1 carrying the upper and lower form blocks 2 and 3 utilizable, as well understood in the art, for transporting a box structure having a wrapper adhering to its bottom into engagement with the lower form block or platen 4 disposed upon the reciprocatory rod 5. Thus held, the box structure and wrapper are carried into coacting relation successively with the rolls 6, 6 for folding the wrapper side panels into contact with the respective box structure side walls, the corner lap turn-in members 7, 7, the rolls 8 for folding the wrapper end panels into contact with the respective box structure end walls 8, the turn-in fingers 9 and the presser bars 10.

Cooperatively related with the wrapping machine W is the delivery end of the conveyor unit C by which wrappers are transported individually and in succession from suitable adhesive-applying mechanism, not shown, into the path of the form blocks 2, 3.

As clearly described in our aforesaid parent application, the conveying unit C comprises a base, not shown, from which rise the spaced side frames 11, 11a tied together by transverse members, not shown, on which are slidable the conveyor frames 12, 12a.

Mounted on sprocket wheels 13 disposed at each end of the conveyor frames 12, 12a are the endless chains 14, 14a carrying the transversely aligned pairs of sheet grippers V. Preferably, the lower spans of the chains 14

and 14a are supported and guided by the members 15 while the upper chain spans are supported by the members 16.

The chains 14 and 14a are operated by the 5 intermittently rotated shafts 17, 17a, Fig. 3, disposed in bearings on the respective conveyor frames 12, 12a. Each shaft 17, 17a carries a gear 18 meshing with a gear 19 keyed to a shaft on which one of the aforesaid 10 sprocket wheels 13 is mounted. Accordingly, the lower spans of chains 14, 14a move step-by-step from left toward the right, Fig. 1, to successively bring individual adhesive-coated wrappers into the path of the form 15 blocks 2, 3.

Operating in timed relation with the wrapping machine form block structure is the oscillatory gear segment 20 which meshes with a gear 21 keyed to a shaft 22. Carried by 20 shaft 22 is a gear, not shown, which meshes with a gear 23 keyed to one end of a shaft 24, which at its other end has the gear 25 keyed thereto, Fig. 2.

Meshing with the gear 25 is a gear 26 keyed 25 to a shaft 27 journaled in the side frames 11, 11a. Gears 28, 28a mounted in bearings in the respective conveyor frames 12, 12a are splined to shaft 27. Meshing with gears 28, 28a are the racks or members 29, 29a disposed 30 for reciprocatory movement in the members 15, 15. Adjustably secured to the racks 29, 29a in any suitable manner, as by the pin-and-slot connections 30, Fig. 1, are the respective pusher bars 31, 31a.

35 Meshing with the spiral gear 26 is the gear 32 keyed to one end of a shaft 33 mounted in bearings in a frame 34 supported by the side frames 11, 11a. Keyed to the other end of shaft 33 is the gear 35 meshing with the gear 40 36 keyed to a shaft 37 mounted in bearings in the frame 34. Gears 38, 38a splined to shaft 37 mesh, respectively, with racks 39, 39a mounted for reciprocatory movement in the respective track structures 40, 40a. Plates 41, 41a, each secured in an adjustable manner longitudinally of and to the respective racks 39, 39a as indicated at 42, Fig. 1, comprise, respectively the knife edges 43 and 43a. Hopper plates 44 adjustably mounted on and 45 longitudinally of the track structure 40, 40a serve to support a stack of blanks B from the bottom of which an individual blank is intermittently removed by the knife edges 43, 43a, as hereinafter particularly described.

50 55 Angle form plates 45 respectively mounted for longitudinal adjustment on the track structures 40, 40a by pin-and-slot connections 46 face cooperating form plates 47 likewise mounted for longitudinal adjustment on track structures 40, 40a by pin-and-slot connections 47b, said track structures 40, 40a comprising, respectively, the downwardly extending members 48, 48a serving as bearings for an upper bending roll 49, Fig. 2.

60 65 Downwardly extending guide plates 50, 50a

likewise carried, respectively, by the track structures 40, 40a, respectively, carry guide structures 51, 51a providing bearings for the lower bending roll 52, Fig. 2. Slidable longitudinally on guide structures 51, 51a are the respective pusher fingers 53, 53a secured, respectively, to the rack structures 39, 39a by the angle plates 54, 54a.

The guide plates 50, 50a carry guide fingers 55, each adjustably mounted thereon in a longitudinal sense by the pin-and-slot connections 56, Fig. 1. Track structures 40, 40a each carry a downwardly and inwardly extending guide finger 57, a pin-and-slot connection 58 permitting longitudinal adjustment of each guide finger with respect to its supporting structure.

Disposed substantially in horizontal alignment with the top surfaces of guide structures 51, 51a are the plate-like members 59, 59a pivoted, respectively, to the guide plates 50, 50a. Members 59, 59a are biased into substantially the positions shown on the drawings by one or more springs 60.

Guide plates 50, 50a are bent inwardly to 90 provide supporting ledges 61, Fig. 4.

Referring to Fig. 1, the constantly rotating shaft 62 carries spiral gear 63 meshing with and driving spiral gear 64 keyed to one end of shaft 65 rotatably supported by the frames 11a and 34. At or adjacent its other end, shaft 65 carries a mitre gear 66 meshing with another mitre gear 67 keyed to a shaft 68 mounted in bearings in the frame 34.

Referring to Fig. 2, shaft 68 carries a cam 69 with which engages a roller 70 mounted at the end of a lever 71 pivoted to the frame 34 at 72. Pivoted to one end of lever 71 is the end of a link 73 whose other end is pivoted to the rod or stem 74 carrying the plunger P1. Spiral spring 75 secured to frame 34 and to lever 71 holds roller 70 in contact with cam 69.

Referring to Fig. 1, shaft 68 carries another cam 76 with which engages a roller 77 mounted on a lever 78 pivoted to the frame 34. Link 79 pivoted to lever 78 is in turn pivoted to the rod or stem 80 of a plunger P2. A spiral spring corresponding to spring 75 is mounted in a similar manner to retain roller 77 115 against cam 76.

The operation is as follows:

Preliminarily, as described in our aforesaid parent application the conveyor frames 12, 12a are adjusted laterally of the side frames 11, 11a to accommodate the desired length of box structure to be formed and the conveyor chains 14, 14a are longitudinally adjusted to bring a sample sheet of the desired width into proper operating position with respect to the form block structure of the wrapping machine.

The hopper plates 44 are now adjusted to conform to the size of the selected blank to be utilized, whereupon a stock B of such blanks 130

are placed within the hopper plates. The plates 41, 41a are correspondingly adjusted and the knife edges 43, 43a are set against the edge of the blank most removed from the wrapping machine.

Plungers P1 and P2 corresponding in size to the interior of the box structure to be made are placed respectively upon the rods 74 and 80.

10 The respective pairs of plates 45 and 47 are now adjusted beneath a blank B of the selected size, the plates 45 being set beneath the cutout corners of the blank most removed from the wrapping machine, and with their 15 respective downwardly extending faces in alignment transversely of the conveyor frames and beneath the transversely scored portion of the blank most removed from the wrapping machine. Plates 47 are likewise 20 set beneath the cutout corners of the blank nearest the wrapping machine with their respective downwardly extending faces in alignment transversely of the conveyor frames and beneath the transversely scored 25 portion of the blank nearest the wrapping machine.

It shall be understood that in effecting this adjustment, the pairs of plates 45 and 47, respectively, are positioned at equal distances 30 from a plane passing vertically through the center of plunger P1 and rod 74 and at right angles to the conveyor frames 12, 12a.

The pairs of plates 55 and 57 are adjusted and fixed in position in a similar manner, 35 with each respective pair positioned at equal distance from a plane passing vertically through the center of plunger P2 and rod 80 and at right angles to the conveyor frames 12, 12a.

40 It will be observed that plungers P1 and P2 must be changed for any change either in length or width of the blanks B but that rolls 49 and 52 are changed only when the blanks differ in length.

45 As described above, individual glued wrappers or sheets are transported into the proper position beneath the form blocks 2, 3, and each sheet, in turn, is released from the gripper units V. In timed relation with this 50 sheet movement, the knife edges 43, 43a reciprocate in response to reciprocation of the racks 39, 39a and on each stroke toward the wrapping machine remove the bottom blank from the stack of blanks B and pass it along the track structures 40, 40a into position above the pairs of plates 45, 47 and beneath the plunger P1. At this stage the plunger P1 descends and pushes the blank B between the respective pairs of form plates 45 and 47 55 which, with guide members 50, 50a, cause partial rupture of the blank at the scored portions, thereby causing the ends and side flaps to assume a substantially vertical position, Fig. 1.

60 In this form, the box is deposited upon the

guide structures 51, 51a whereupon the plunger P1 rises preparatory to its action on the succeeding blank B which is now fed forward by knife edges 43, 43a. As the latter again move forward pusher fingers 53, 53a likewise move forward and bend the rear side flap of the blank toward the wrapping machine, the rear corner entering the space beneath said fingers. During continued forward movement, the forward side flap of the 70 box engages stationary form plates 47 under which the now partially formed box structure is pushed, from whence it passes through the bending or shaping rolls 49 and 52, the opposite end flaps of the box structure extending vertically and passing exteriorly of the rolls through the passages 81. Due to this 75 operation, the tendency of the side flaps to return to their original or flattened position is lessened and the finished article will be 80 85 of improved appearance.

Fingers 53, 53a move the shaped box structure along the guide structures 51, 51a and deposit it on the plates 59, 59a in the path of the plunger P2 which now descends, enters 90 the box structure, and carries it downwardly, the plates 59, 59a swinging on their pivots against the springs 60 and entering the recesses 82 in the guide plates 50, 50a, Fig. 4, to permit such movement of the box structure. 95

During continued descent of the plunger P2, the box structure is forced downwardly between the pairs of form plates 55 and 57 into the shelf members 61, along which, after retraction of plunger P2, the pusher members 100 31, 31a advance the box structure into the path of the form blocks 2, 3 where it may be held by the spaced resilient plates 83, as particularly described in our aforesaid parent application.

105 The upper form block structure may be provided with an arrangement, not shown, but of a character substantially as illustrated in U. S. Letters Patent No. 1,065,330, for holding the box structure thereon. Briefly, this arrangement comprises spring holders, 110 outwardly flared at their ends, and secured adjacent their other ends within the periphery of the form block structure, said springs engaging the opposite end flaps of the box structure to releasably secure the entire box structure to the upper form block structure. 115

120 The partially formed box structure and the adhesive-coated wrapper moves downwardly through the machine to perform the wrapping operation, as is well understood in the art, and on its upward movement is suitably stripped from the upper form blocks and ejected from the machine.

125 What we claim is:

1. Box shaping apparatus comprising means for feeding a box blank in one direction, means for simultaneously effecting a partial shaping operation and passing the blank in another direction, and means oper- 130

able for again feeding the blank in said one direction and for bending contiguous portions thereof substantially into face to face contact completing the shaping operation.

- 5 2. Box shaping apparatus comprising means for feeding a box blank in one direction, means for simultaneously effecting a preliminary shaping operation and passing the blank in another direction, means oper-
10 able for again feeding the blank in said one direction, and means to bend contiguous portions of the blank substantially into face to face contact to effect a final shaping opera-
15 tion.
- 15 3. Box shaping apparatus comprising a supporting member, a box blank shaping roll carried thereby, and means for adjusting said member transversely of the path of movement of the blank, whereby rolls of differ-
20 ent lengths may be utilized.

4. Box shaping apparatus comprising means to feed scored, unshaped box blanks from a stack thereof comprising means to engage and exert pressure on an edge of an
25 end blank of said stack, form plates, means engaging faces of said blanks in succession and co-operating with said form plates to bend said blank along the scoring, and means operating upon bent blanks in succession comprising structure to fold wall components of said blanks adjacent said scoring substantially and temporarily into face to face contact.

5. Apparatus of the character described comprising means to retain box blanks in stack formation, a plunger, bending structure, and transporting means simultaneously to move a blank from said stack into the path of said plunger, and another blank from the path of said plunger to said bending structure.

6. Apparatus of the character described comprising means to retain box blanks in stack formation, a plunger, bending structure and a reciprocating transfer structure
45 actuated in timed relation to said plunger simultaneously to transport a blank from said stack into the path of said plunger, and another blank from the path of said plunger to said bending structure.

50 7. Box making apparatus comprising means to feed scored, unshaped box blanks from a stack thereof comprising means to engage and exert pressure on an edge of an end blank of said stack, means to bend said
55 blanks in succession along the scoring thereof, wrapping machine form-block structure, and means to transfer bent blanks in box-simulating form into the path of said structure.

60 8. Box making apparatus comprising means to retain box blanks in stack formation, a shaping plunger, form-block structure, and reciprocating structure adapted during successive reciprocations to transport
65 a box blank intermittently in the same direc-

tion from said stack to said plunger, and from said plunger to said form-block structure.

9. Box making apparatus comprising means to retain box blanks in stack forma-
70 tion, a shaping plunger, form-block structure, and reciprocating structure adapted during successive reciprocations to transport a box blank intermittently in the same direc-
75 tion from said stack to said plunger, and from said plunger to said form-block structure, and means to transport the shaped blanks in box-simulating form into the path of said form-block structure.

10. Box-shaping apparatus comprising means to bend portions of a box blank destined to form opposite vertical walls of a box with respect to the portion destined to form the box bottom, means to feed said blank while bent, and a member successively 85 engaging said portions to iron them into engagement with the box bottom.

11. Box-making apparatus comprising means to feed box structures toward wrapping structure, means to feed freshly coated wrappers toward said structure, and reciprocating mechanism effecting aligned relation of box structures and wrappers in succession for movement into the path of said wrapping structure.

12. Box-making apparatus comprising means to feed box structures toward wrapping structure, conveyor mechanism movable always in one direction to feed freshly coated wrappers toward said structure, and reciprocating mechanism effecting movement in succession of box structures into superposed aligned relation with wrappers for movement therewith into the path of said wrapping structure.

13. Box-making apparatus comprising conveyor mechanism intermittently movable in one direction to feed freshly coated wrappers into the path of wrapping structure, a reciprocating plunger to move box structures into superposed aligned relation with wrappers, and reciprocating structure movable with said conveyor mechanism in one direction to move aligned box structures into the path of said wrapping structure, and simultaneously to transport box structures into the path of said plunger.

14. Box-making apparatus comprising conveyor mechanism intermittently movable in one direction to feed freshly coated wrappers into the path of wrapping structure, a reciprocating plunger to move box structures into superposed aligned relation with wrappers, and reciprocating structure movable with said conveyor mechanism in one direction to move box structures in said wrapper-registering relation into the path of said wrapping structure, simultaneously to transport box structures into the path of said plunger, and to move a wrapped box from the

path of movement of the wrapping structure.

15. Box-making apparatus comprising a reciprocating plunger adapted to engage and transport box structures, and a reciprocating carriage for transporting box structures received from said plunger into the path of a wrapping structure and for transporting box structure to said plunger.

16. Box-making apparatus comprising box-shaping mechanism, form block structure, and a reciprocating structure for transporting box blanks to said mechanism and shaped blanks in box-simulating form into the path of said form block structure.

17. Box-making apparatus comprising means for feeding wrappers toward a wrapping structure, a reciprocating plunger adapted to move shaped box blanks in box-simulating form into superposed aligned relation with said wrappers, and reciprocating structure for transporting shaped box blanks into the path of movement of said plunger and moving said box blanks in box-simulating form to said wrapping structure while maintaining said aligned relation.

18. Box-shaping apparatus comprising means for feeding a box blank in one direction, means for shaping the box blank by bending portions thereof destined to form box walls substantially into face to face contact with an intermediate blank portion and for simultaneously passing the blank in another direction, and means operable for again feeding the blank in said one direction.

19. Box-shaping apparatus comprising means for feeding a box blank in one direction means timed therewith for shaping the box blank by bending portions thereof destined to be box walls into face to face contact with an intervening portion and simultaneously for passing the blank in another direction and means timed with said feeding means for again feeding the blank in said one direction.

20. Box-shaping apparatus comprising means for simultaneously bending portions of a box blank destined to form opposite walls of a box, and a member successively engaging said bent portions to effect temporary face to face contact thereof with the box bottom.

21. The continuous method of forming boxes from box blanks which comprises bending each blank in succession to bring the portions thereof adapted to form opposite vertical walls into engagement with the box bottom, without substantial delay feeding the blanks as thus shaped individually in succession to a station, and at said station forming in succession boxes from said shaped blanks by securing the wall portions thereof in box-forming position by adhesive-coated sheet material.

THEODORE A. FEDERWITZ.
WALTER T. BAILEY.
